UNITED STATES PATENT OFFICE.

MORRIS P. HOLMES, OF CLAREMONT, NEW HAMPSHIRE, ASSIGNOR TO SULLIVAN MACHINERY COMPANY, A CORPORATION OF MASSACHUSETTS.

MINING APPARATUS.

Application filed April 18, 1919, Serial No. 291,115. Renewed May 5, 1927.

My invention relates to mining apparatus.

It has for its object to provide an improved mining apparatus. A further object 5 of my invention is to provide an improved machine of the so-called "universal" type, adapted to cut a kerf at any one of a variety of angles in the face or in a plurality of planes relative to the bottom. A further 10 object of my invention is to provide an improved machine adapted during cutting to be attached to the face in an improved manner, preferably through improved combined supporting and drilling members carried by 15 the machine. A still further object of my invention is to provide improved and simplified feeding and adjusting mechanisms whereby a machine of the type set forth may be adapted to all of the varying usages 20 of service and especially of entry driving service, with increased facility at the same time that an exceedingly rugged and powerful construction is produced. These and 25 other objects of my improved construction will, however, hereinafter more fully appear.

In the accompanying drawings I have shown for purposes of illustration one embodiment which my invention may assume 30 in practice.

In these drawings,—

Fig. 1 is a side elevation of this embodiment of my invention, showing the machine on its truck.

Fig. 2 is a plan view of the construction shown in Fig. 1, the front end being broken away.

Fig. 3 is a plan view, partially in section, showing the combined supporting and 40 drilling members and a portion of the feeding mechanism therefor.

Fig. 4 is a side elevation, partially in section, showing the cutter chain driving mechanism and the mechanism for angularly 45 moving the cutter bar, as well as a portion of the feeding mechanism.

Fig. 5 is an enlarged sectional view taken on line 5—5 of Fig. 4.

Fig. 6 is a detail sectional view taken on 50 line 6—6 of Fig. 1.

Fig. 7 is a detail sectional view taken on line 7—7 of Fig. 1.

Fig. 8 is a diagrammatic view showing the machine rotated to vary the position 55 of its bar.

Fig. 9 is a diagrammatic view showing a modified construction of the machine adapted to be swiveled into a plurality of positions.

Fig. 10 is a diagrammatic view showing 60 the machine and bar in their several positions during the kerf cutting operation.

In this illustrative construction, it will be observed that I have shown a mining machine frame 1 having operatively connected cutting mechanism, hereinafter described, and reciprocable and rotatable, as also hereinafter described, relative to a lower, longer frame 2 having an open front end and upstanding side members and carrying at its rear end a usual conductor reel 3. This frame 2 is in turn mounted on a horizontal swivel or turret 4 on the front end of a lower, flat topped supporting frame 5 pivotally supported transversely at its 75 front end at 6 on the front axle 7 of a wheel mounted truck 8. As shown, this frame 5 is tilttable vertically about its pivot 6 by means of a jack screw 9 carrying a suitable nut 10 journaled in suitable bearings 11 formed on the under side of the rear end of the truck 8 and connected to the frame 5 through a pivotal connection 12.

Thus it will be observed that by rotating the nut 10, as for instance by inserting a bar 85 in suitable openings 13 therein, the frame 5 may be tilted vertically to tilt the machine 1 about the front axle 7 of the truck 8. It will also be noted that this truck 8 is driven by a separate motor 14 connected to the front truck wheels 15 by a usual chain and sprocket connection 16, the motor being controlled by a usual controller 17, herein carried beneath the truck frame and controllable by a removable controlling lever 18 95 extending upward toward the top of the machine. This will be observed that the machine may be transported as usual from place to place on its truck under its own power, and when in any place may be swung 100 about its swivel 4, or tilted about the front axle 7 of the truck to adjust the level of the same relative to the bottom as desired by simply adjusting the nut 10.

Referring more particularly to the cutting mechanism carried by the frame 1, it will be observed that the same herein includes a usual cutter bar 19 having a cutter chain 20 rotatable about the same and carrying the usual cutter bits 21. This bar is, as 110

shown, preferably pivotally mounted at its rear end on the front end of the frame 1 so that it may be swung angularly relative to a vertical axis thereon. Referring more particularly to the construction shown in Fig. 4, it will be observed that the rear end of this bar 19 is fixed to a suitable bracket 22 journaled at 23 on a vertical axis on a cooperating depending portion 24 on a front head 25 10 fixed to the frame 1 so that the bar may be moved angularly in a transverse plane. Also, it will be observed that the bar is swung and the cutting mechanism thereon is driven from a motor 26 carried in the 15 frame 1. Herein the armature shaft 27 of this motor is longitudinally disposed and carries on its front end a bevel pinion 28 meshing with a larger bevel pinion 29 on a short vertically disposed shaft 30 journaled 20 in suitable bearings in the head 25 and carrying a spur gear 31 on its lower end. This gear 31 in turn meshes with a larger cooperating gear 32, which is formed on and substantially midway between the ends of an 25 elongated sleeve member 33 freely rotatable on a longer vertical shaft 34 suitably journaled on the head 25 and disposed in front of the shaft 30. This sleeve 33, as shown, extends upward from the gear 32 and downward therefrom, the same herein acting as a driving element for both the cutting mechanism and the bar swinging mechanism.

Referring first to the cutter chain driving mechanism, it will be noted that herein the 35 lower end of this sleeve is journaled in the head 25 and has operatively connected thereto, as through a usual clutch 35 (not shown in detail), a cutter chain driving sprocket 36 driving the cutter chain 20 in the usual 40 manner. Referring now to the bar swinging mechanism, it will be observed that the upper end of the sleeve is also similarly journaled in the head 25 and is operatively connected, through differential driving 45 mechanism, with the upper end of the shaft 34. As this differential driving mechanism per se forms no part of my present invention and is described and claimed in my copending application, Serial No. 260,708, filed 50 Nov. 1, 1918, a detail description of the same herein seems unnecessary other than to say that the same includes an eccentric 37 rotatable with the upper end 38 of the sleeve and driving a differential gear 39, which meshes 55 with cooperating internal gears 40 and 41 of different diameter, of which the gear 40 is controlled by a friction clutch 42, while the connection of the two gears is controlled by a friction clutch 43, the two clutches being 60 controlled by a controlling hand wheel 44. Thus the gear 40 may be locked to the casing or the two gears 40 and 41 locked together in such a manner as, through the fixing of the latter gear, by a spline 45 to the upper 65 end of the shaft 34, to rotate that shaft

slowly or rapidly in opposite directions. As shown, the shaft 34 carries on its lower end a pinion 46 meshing with an idler pinion 47, which in turn meshes with a larger gear 48 carried on the lower end of a stub shaft 49 70 journaled in the bar supporting member 22 and in turn carrying on its upper end a pinion 50 meshing with an arcuate rack 51 formed on the front of the head 25. Thus, it will be observed that through control of 75 the controlling member 44 the cutter bar 19 may be swung in either direction about its pivot and at either a slow or cutting speed or a fast or moving speed, as desired; the cutting mechanism, i. e. the cutter chain 20, 80 being controlled independently through the clutch 35 so that that mechanism may be thrown out of operation whenever desired. As shown, it will also be noted that a reversible controller 52 for the motor 26 is provided between the front end of the frame 1 and the controlling mechanism, including the controlling member 44, so that the controller operating means 53 may be conveniently located relative to the member 44. 85 90

Operatively connected to the frame 1 and disposed between the latter and the frame 2, is my improved mechanism for rotating the entire frame 1 relative to its supporting frame 2. As shown in Fig. 6, the frame 1 is provided with a round front end member 54 rotatably mounted in suitable arcuate bearings 55 carried on upstanding members 56 provided on opposite sides of the front end of the frame 2. As shown, this member 54 is provided with inwardly disposed extensions 57 providing journals 58 for longitudinally disposed supporting members 59, herein in the form of feed members extending longitudinally beyond the opposite ends 105 of the frame 1. Herein it will also be observed that these members 59 are fixed, as by nuts 60 threaded on their rear ends, to a turning frame or wheel 61, which is itself rotatable on a horizontal axis on a suitable bearing 62 formed on an upstanding support 63 at the rear of the frame 2. Thus it will be noted that the frame 1 is supported by the bearings 55 and the bearing 62 at its opposite ends and may turn about a horizontal axis and thereby turn the cutting mechanism relative to the face. It will also be observed that the support 63 is provided with a flange 64 and a cooperating removable clamping plate 65 attached to it by 110 screws 66 in such a manner as to hold the parts in their desired relation. Also, it will be observed that in the flange 64 suitable apertures are provided so that one or more locking pins 67 may pass therethrough and into corresponding apertures formed in the member 61 to lock the latter in any desired angular position. Attention is also directed to the fact that the member 61 is provided with a plurality of radially disposed open 115 120 125 130

ings 68 adapted to receive a bar or the like so that the member 62 and the connected mining machine mechanism and cutter bar may, when the pins 67 are released, be 5 manually turned angularly to the desired position.

Operatively connected to the motor 26 and also preferably driven from the rear end of the armature shaft, is my improved mechanism for feeding the machine frame 1 during cutting. This mechanism, as shown in Fig. 5, includes a worm 69 carried on the rear end of the armature shaft 27 and meshing with a worm gear 70 operatively connectible through friction clutch elements 71, including a movable controlling element 72, with a sleeve 73 splined on an inner transversely disposed shaft 74. As shown, this shaft 74 carries on its opposite ends 20 combined journal and worm members 76 which are rotatable in suitable bearings 75 on the rear end of the frame 1 and normally rotate freely on the shaft and are connectible therewith at will by usual clutch mechanisms 77 including members splined on the ends of the shaft. These worm members 76 in turn mesh with worm gears 78 (Fig. 3) 25 freely rotatable on rear threaded sleeve members 79 forming continuations of sleeve members enclosing the rear ends of threaded portions 80 formed on the members 59 and extending rearward thereon from points adjacent the members 57. Each of these gears 30 78 is in turn provided with a clutch face 81 engageable with a reciprocable double-ended clutch member 82 splined to the sleeve 79. Also, it will be observed that reciprocable double-ended clutch members 83 are splined on the members 59 adjacent the member 61, 35 and are adapted to engage with cooperating clutch teeth 84 formed on that member when in one position. Thus, it will be observed that when the clutch member 82 is connected to the clutch teeth 81 and the clutch member 83 is connected to the clutch teeth 84, the sleeve 80 will be fed bodily forward to feed the frame 1 with a friction controlled feeding movement relative to the frame 2 and the work at a slow or cutting speed.

Also operatively connected to the motor and herein similarly driven from the shaft 74, is my improved mechanism for feeding the machine frame in the opposite direction, i. e., from the work. This mechanism, as shown, includes a pinion 85, (Fig. 5) preferably formed integral with the sleeve 73 and constantly meshing with a gear 86 (Fig. 3) carried on a lower transverse shaft 87 suitably journaled in the frame and having 50 bevel gears 88 on its opposite ends meshing with bevel gears 89 rotatable on the sleeves 79 and disposed between the members 82 and 83 and having clutch teeth 91 and 92 engageable by the clutch teeth on the inner ends of the members 82 and 83. Thus, it

will be observed that when the clutch members 82 are thrown out of engagement with the clutch teeth 81 and connected with the clutch teeth 92, the sleeves 79 are rotated relative to the threaded members 80 in such a manner as to move the machine frame 1 in an opposite direction at a greatly increased speed, both the slow and fast feeds thus being driven through the friction mechanism 71.

Preferably also operatively connected to the motor is also improved means for drilling the face so that the machine may be supported thereon. These means may, obviously, assume various forms. Herein, they are preferably formed integral with the members 80, drills, herein in the form of rotary members or augers 93, being formed on the front ends of the members 59 and adapted to enter the face and thereby enable the members 59 to be supported by the face and cooperate with the truck in supporting the machine as it is moved toward or from the work. As shown, the members 59 and their drills are rotated by power and fed forward relative to the machine frame 1 and within the sleeves 79, by the threaded connections between the parts when the clutch 83 is connected with the clutch teeth 91. As a result, when the truck is fed forward or toward the face as these drills 93 are rotated, the latter are caused to bore their way into the face and be securely lodged therein to such a depth as to form a suitable support. Here it will also be noted that in order to limit the drilling movement of the drills and the forward movement of the machine frame on the members 59, and also to operatively connect the front ends of the members 59, a spanner 94 is loosely mounted on the outer ends of the members 59 and held in adjusted position relative thereto by clamping rings 95 located on opposite sides of the spanner ends and adapted to be held in position by screws 96. It will also be noted that the desired rigidity of the support is further increased by the provision of a second spanner 97 adjacent the front end of the machine frame 1 and herein formed integral with the members 57. Attention is also directed to the fact that this spanner 97 is preferably provided with a vertically disposed T-shaped groove 98 adapted to receive a vertically disposed web member 99 formed on the front of the frame 1, so that this spanner is not only pushed forward by the machine as the latter moves forward, but is retracted by and with the machine.

In the operation of my improved construction, the machine is run into the room or entry on its truck. The truck is then stopped, and the machine rotating, swiveling, or tilting, means are then adjusted (Figs. 8, 9) as necessary in order to direct

the bar into the desired plane of operation. By these adjusting means it will be noted that the bar may be disposed either vertically or at substantially any desired angle to the vertical, and at any desired angle with respect to the horizontal, depending upon the conditions encountered. With the angle of the bar so adjusted, the drills 93 are then operated as the truck is fed toward the face so that these drill members are embedded therein. The cutter bar and machine are then operated (Fig. 11) as described in my copending application, i. e. the cutter bar is first swung laterally to its sumping position, then through the slow feed mechanism hereinabove described the machine frame is fed forward on the truck to force the bar into the coal; then the bar is swung laterally and, last, by reversing the feed the frame is retracted on the truck, herein through the use of my improved fast reverse feed mechanism. When the cut has thus been made and the machine frame 1 has been thus returned to its normal or retracted position, and the drilling members are withdrawn from the face, the machine is transported to another place.

As also illustrated in Fig. 9, it will be evident that when desired my improved machine may be similarly utilized in cutting room necks or the like, the machine and drills then first being swiveled into position, herein at right angles to the truck, and the drills then being moved toward the face and relative to the truck by improved mechanism. As shown, this mechanism includes extensions 104 fixed on the rear ends of the drills and a crosshead 105 secured thereto by nuts 106 and adjustable bodily therewith by means of an adjusting screw 107 operable by a hand wheel 108 and threaded into the rear end of the support 63. Thus it will be observed that when the machine and drills are swiveled into position, the drills 45 may be fed forward and into the face by a manual rotation of the hand wheel 108, to produce the same result as when the truck is fed forward. Here it will also be noted that this feeding mechanism will in no way interfere with the operation of the power feed for the drills, heretofore described, the construction being such that these feeding mechanisms may be selectively used as occasion requires.

As a result of my improved construction, it will be observed that not only may the cutter bar be swung in the various positions described in my copending application mentioned above, but the machine frame may be adjusted bodily through its rotating mechanism, its swivel mechanism, and its tilting mechanism, in such a manner as to enable the machine to meet a wider range of conditions. Attention is also directed to the fact that through the use of my im-

proved supporting means, an exceedingly sturdy support is provided which is readily adapted to be secured in position and, since it is operated entirely by the power of the machine, to be utilized with greatly increased facility and speed. These and other advantages of my improved construction will, however, be clearly apparent to those skilled in the art.

While I have in this application specifically described one embodiment which my invention may assume in practice, it is to be understood that this form thereof is used for illustrative purposes only and that the invention may be modified and embodied in various other forms without departing from its spirit or the scope of the appended claims.

What I claim as new and desire to secure by Letters Patent is:

1. In a mining apparatus, a support, a mining machine thereon having cutting mechanism adapted to cut a plane kerf, and a drilling means operative to penetrate a face and then to remain stationary and to support said machine on such face during the entire operation of the cutting mechanism.

2. In a mining apparatus, a support, a plane kerf cutting mechanism thereon, and face penetrating drilling means adapted to be driven by said machine and relative to which the latter is longitudinally movable for supporting the machine on the face.

3. In a mining apparatus, a support, a mining machine thereon having cutting mechanism, and means adapted to cause a portion of the weight of said machine to be borne by a face including a plurality of drilling means relative to which said machine is longitudinally movable.

4. In a mining apparatus, a support, a mining machine thereon having a swinging cutter bar, and means for supporting said machine during cutting either through swinging or bodily movement of said bar including a plurality of laterally spaced drilling means for supporting said machine on a face both before and during cutting.

5. In a mining apparatus, a truck, a plane kerf cutting mining machine thereon having cutting mechanism, and means including a rotatable drilling member along which said machine may be fed during cutting for supporting said machine on the face.

6. In a mining apparatus, a truck, a mining machine thereon having cutting mechanism, and means including a plurality of rotatable drilling members for transmitting the weight of the machine to the face.

7. In a mining apparatus, a truck, a plane kerf cutting mining machine thereon having cutting mechanism, and means driven by said machine including a rotatable drilling member for supporting said machine on the

- face, said drilling member constituting a supporting guiding means for said machine during movements of the latter bodily towards and from the face.
5. 8. In a mining apparatus, a truck, face drilling means carried thereon, and a plane kerf cutting mining machine on said truck movable relative to said means.
9. In a mining apparatus, a truck, face drilling means carried thereon, and a plane kerf cutting mining machine on said truck movable in opposite directions relative to said means.
10. In a mining apparatus, a truck, face drilling means carried thereon, and a plane kerf cutting mining machine on said truck movable at different speeds relative to said means.
11. In a mining apparatus, a truck, face drilling means carried thereon, and a plane kerf cutting mechanism on said truck movable longitudinally relative to said means.
12. In a mining apparatus, a truck, face drilling means carried thereon, and a plane kerf cutting mining machine on said truck driving said means and movable relative thereto.
13. In a mining apparatus, a truck, face drilling supporting means thereon, a plane kerf cutting mining machine on said truck driving said means and movable relative thereto and means for vertically adjusting one end of one of said elements.
14. In a mining apparatus, a truck, face drilling supporting means thereon, a plane kerf cutting mining machine on said truck driving said means and movable relative thereto and means for adjusting both of said last mentioned elements relative to the horizontal.
15. In a mining apparatus, a truck, face drilling supporting means thereon, a plane kerf cutting mining machine on said truck having kerf cutting mechanism, and means whereby said face drilling supporting means may be rotated about a longitudinal axis offset from its axis of rotation during drilling.
16. In a mining apparatus, a truck, face drilling supporting means thereon, a plane kerf cutting mining machine having kerf cutting mechanism on said truck, and means for rotating both of said last mentioned elements about a longitudinal axis.
17. The combination with a truck, of a plane kerf cutting mining machine having kerf cutting mechanism, face drilling means supporting said machine on said truck, and means for tilting said means about a transverse axis.
18. The combination with a truck, of a plane kerf cutting mining machine, face drilling means supporting said machine on said truck, and means whereby said means may be swung about a vertical axis.
19. The combination with a truck, of a plane kerf cutting mining machine having kerf cutting mechanism, face drilling means supporting said machine on said truck, and means for adjusting said means about a longitudinal axis.
20. The combination with a truck, of a plane kerf cutting mining machine, face-drilling means supporting said machine on said truck, and means for tilting and swinging said means about axes one of which makes an angle with a line parallel to a line parallel to the other.
21. The combination with a truck, of a plane kerf cutting mining machine having kerf cutting mechanism, face drilling means supporting said machine on said truck, and means for adjusting said machine in a vertical plane on said truck.
22. The combination with a truck, of a plane kerf cutting mining machine having kerf cutting mechanism, face drilling means supporting said machine on said truck, and means for adjusting said machine in a vertical plane and about a longitudinal axis.
23. The combination with a truck, of a plane kerf cutting mining machine having kerf cutting mechanism, face drilling machine supporting means, and means for selectively moving one of said elements relative to the other.
24. The combination with a truck, of a plane kerf cutting mining machine having kerf cutting mechanism, face drilling means supporting said machine, and means for moving said means relative to said machine.
25. The combination with a truck, of a plane kerf cutting mining machine having kerf cutting mechanism, face drilling means supporting said machine, and means for moving said machine relative to said means.
26. The combination with a truck, of a plane kerf cutting mining machine having kerf cutting mechanism, face drilling means carrying said machine, and means for simultaneously operating said drilling means and propelling said truck.
27. The combination with a truck, of a plane kerf cutting mining machine, machine guiding means on said truck, and means whereby said guiding means may be rotated about a longitudinal axis lying in a common plane therewith and said machine moved longitudinally along said guiding means relative to said truck.
28. In a mining apparatus, a truck, a mining machine having a motor and a swinging cutter bar adjustable by said motor, said machine being rotatable on said truck on a horizontal axis and movable by power from said motor longitudinally of said truck relative to the latter, and bearing supports therefor on opposite ends of said truck.
29. In a mining apparatus, a wheeled truck, a mining machine including a motor

disposed on said truck and rotatable on a longitudinal axis coincident with the axis of rotation of said motor and having a cutter bar independently pivoted on the front end thereof, and a machine rotating wheel on said machine arranged expressly for manual rotation.

30. In a mining apparatus, a truck, a plane kerf cutting mechanism, a machine having a cutter bar and a driving motor therefor rotatable on a longitudinal axis on said truck, and coaxially disposed bearings therefor of different diameters carried on opposite ends of said truck, one of said bearings permitting said motor to pass therethrough, and guiding means carried on said truck for said machine along which the same is movable longitudinally relative to said truck while said motor passes through said bearing.

31. In combination, a support, a mining machine thereon having a pivoted cutter bar rotatable on a longitudinal axis on said support, and means rotatable therewith for feeding said bar relative to said support rectilinearly during cutting and swinging said bar in a plane.

32. In combination, a support, a mining machine thereon having a pivoted cutter bar rotatable on a longitudinal axis on said support, and means rotatable therewith for feeding said bar longitudinally of said support and swinging said bar in a plane.

33. In combination, a support, kerf cutting mechanism thereon including a swinging cutter bar rotatable on a longitudinal axis on said support, means rotatable therewith for feeding said bar longitudinally of said support, and means for swinging said bar in a plane.

34. In combination, a support, kerf cutting mechanism thereon including a pivoted plane cutter bar rotatable on a longitudinal axis on said support, means rotatable therewith for feeding said bar longitudinally of said support, and means for swinging said bar in its plane.

35. In combination, a support, a kerf cutting mechanism thereon including a swinging cutter bar rotatable on a longitudinal axis on said support, means rotatable therewith for feeding said bar longitudinally of said support, and means for swinging said bar in any of a plurality of intersecting planes.

36. In combination, a support, a kerf cutting mechanism thereon including a pivoted plane cutter bar rotatable on a longitudinal axis on said support, means rotatable therewith for feeding said bar longitudinally of said support, and means for swinging said bar in its plane in different positions relative to the axis of rotation.

37. In a mining apparatus, a plurality of face engaging threaded feeding members, a

mining machine, and means for feeding said machine relative thereto.

38. In a mining apparatus, a plurality of face engaging threaded feeding members, a mining machine, and means for feeding said machine relative thereto at different speeds.

39. In a mining apparatus, a plurality of face engaging threaded feeding members, a mining machine, and means for feeding said machine relative thereto at different speeds in opposite directions.

40. In a mining apparatus, a support, a plurality of threaded feeding members thereon, a mining machine thereon, nut members cooperating with said threaded members, and means for rotating one or both of said members at will.

41. In a mining apparatus, a support, a plurality of threaded feeding members thereon, a mining machine on said feeding members, and clutch means for selectively feeding said machine on said members at different speeds.

42. In a mining apparatus, a support, feeding members thereon, a plurality of sleeve members on said members, a mining machine connected to certain of said sleeve members, and means including clutch mechanism for selectively feeding certain of said sleeve members relative to said feeding members.

43. In a mining apparatus, a support, feeding members thereon, a plurality of sleeve members on said members, a mining machine connected to certain of said sleeve members, and means including clutch mechanism for selectively feeding certain of said sleeve members in opposite directions at different speeds on said feeding members.

44. In a mining apparatus, a support, threaded feeding members thereon, a plurality of sleeve members on said threaded members, a mining machine connected to certain of said sleeve members, and means including clutch mechanism for selectively rotating said sleeve members.

45. In a mining apparatus, a support, longitudinally disposed machine supporting and feeding drills thereon, a machine movable longitudinally thereon, and a spanner connecting said supporting members.

46. In a mining apparatus, a support, longitudinally disposed machine supporting drills thereon, a machine movable longitudinally thereon, and a spanner connecting said supporting members and movable with said machine.

47. In a mining apparatus, a support, longitudinally disposed machine supporting drills thereon, a machine movable longitudinally thereon, and cooperating spanners one movable with said machine and the other carried on said members.

48. In a mining apparatus, a wheeled truck, longitudinally disposed machine sup-

porting drills thereon, a machine oppositely movable longitudinally on said drills, and a spanner movable with said machine.

49. In combination, a truck, a frame tiltable on a transverse pivot thereon, a longitudinally disposed mining machine on said frame including a cutter bar swingable by power in a plane about a pivot perpendicular thereto, and means for feeding the machine longitudinally relative to said truck and rotating the machine as a whole about a longitudinal axis and relative to said frame.

50. In a mining apparatus, a support, a plane kerf cutting mining machine thereon having a cutter bar, face drilling means carrying said machine, and means for moving said drilling means toward the face during the drilling operation.

51. In a mining apparatus, a support, a plane kerf cutting mining machine thereon having a cutter bar, face drilling means carrying said machine and operatively connected to said machine, and means for moving said drilling means toward the face during the drilling operation.

52. In a mining apparatus, a support, a plane kerf cutting mining machine thereon having a cutter bar, face drilling means supporting said machine and swiveled on said support, and means for moving said drilling means toward the face during the drilling operation.

53. In a mining apparatus, a support, a plane kerf cutting mining machine thereon having a cutter bar, face drilling means supporting said machine and swiveled on said support and driven by said machine, and means for moving said drilling means toward the face during the drilling operation.

54. In a mining apparatus, a support, a plane kerf cutting mining machine thereon having a cutter bar, face drilling means supporting said machine and swiveled on said support and operatively connected to said machine, and selectively operable means for moving said drilling means toward the face during the drilling operation when swiveled into different positions relative to said support.

55. In a mining apparatus, a support, mining mechanism thereon having a cutter bar, face engaging cooperating supporting means, means for moving said means about axes lying in intersecting planes and relative to said support, and means for moving said bar relative to said cooperating supporting means.

56. In a mining apparatus, a support, mining mechanism thereon having a cutter bar, face engaging cooperating supporting means for said bar, means for adjusting said means about a longitudinal axis, and means for moving said bar relative to said cooperating supporting means.

57. In a mining apparatus, a support, cooperating face drilling supporting means thereon, means for inserting the same into the face, kerf cutting mechanism movable longitudinally of said cooperating supporting means, and means for moving said kerf cutting mechanism relative to said cooperating supporting means to cut a kerf in the face.

58. In a mining apparatus, a support, cooperating face drilling supporting means thereon, means for inserting the same into the face, kerf cutting mechanism movable relative to said cooperating supporting means, and means for moving said kerf cutting mechanism longitudinally and angularly relative to said drilling means after the latter are inserted in the face.

59. In a mining apparatus, a support, mining mechanism thereon having a swinging cutter bar, face drilling cooperating machine supporting means, means for moving said drilling means toward the face during the drilling operation, means for moving said machine toward the face when said bar is disposed at an angle thereto, and means for swinging said bar.

60. In a mining apparatus, a support, cooperating face engaging supporting means thereon, kerf cutting mechanism movable longitudinally of said cooperating supporting means, and means for angularly adjusting said cutting mechanism and said cooperating supporting means about an axis disposed longitudinally of the latter.

61. In a mining apparatus, a support, cooperating face engaging supporting means carried thereby, kerf cutting mechanism, means for moving said supporting means relative to said support into engagement with the face, and means for moving said kerf cutting mechanism longitudinally of said cooperating supporting means to cut a kerf in the face.

62. In a mining apparatus, a support, a machine guiding means comprising a plurality of parallel face engaging members supported on said support for rotation about a longitudinally extending axis lying between them, and a mining machine slidable along said members.

63. In a mining apparatus, a support, and machine guiding means comprising spaced guiding members and pivotally mounted upon said support for movement into planes whose traces on a working face will lie in intersecting lines, a mining machine longitudinally movable along said members, and means driven by said mining machine for rotating said members.

64. In a mining apparatus, a support, machine guiding means mounted on said support for rotation about a longitudinally disposed axis, said machine guiding means comprising a pair of guiding members arranged

on opposite sides of and in a common plane with said axis, and a mining machine slideable along said guiding means and comprising a pivoted cutter bar adapted to swing in a plane parallel to the plane of said guiding means.

65. In a mining apparatus, a support, and machine supporting and guiding means carried thereby including a plurality of face 10 engaging members, drilling means at the forward end of said members, a machine slideable along said members, and transmission mechanism driven by said machine for rotating said members and for feeding said 15 machine longitudinally of said members.

66. In a mining apparatus, a support, guiding means for a mining machine carried by said support and supported at spaced points upon said support and extending beyond the end of said support, pivotal 20 supporting means whereon said guiding means may be rotated into different planes passing through and including a longitudinally extending axis, and a mining machine slideable along said guiding means and movable to a position where its center of mass lies outside of said pivotal supporting means and having a swinging bar.

In testimony whereof I affix my signature.

MORRIS P. HOLMES.

CERTIFICATE OF CORRECTION.

Patent No. 1,670,152.

Granted May 15, 1928, to

MORRIS P. HOLMES.

It is hereby certified that error appears in the printed specification of the above numbered patent requiring correction as follows: Page 1, line 84, for the misspelled word "rotaing" read "rotating"; page 5, lines 32 and 38, claims 13 and 14, after the word "thereto" insert a comma; same page, line 52, claim 16, strike out the words "on said truck" and insert the same to follow after the word "machine" line 51; and that the said Letters Patent should be read with these corrections therein that the same may conform to the record of the case in the Patent Office.

Signed and sealed this 10th day of July, A. D. 1928.

(Seal)

M. J. Moore,
Acting Commissioner of Patents.
